UNITED STATES PATENT OFFICE.

ALVIN BROWN, OF AURORA, ILLINOIS.

STREET-SWEEPER.

SPECIFICATION forming part of Letters Patent No. 637,704, dated November 21, 1899.

Application filed May 17, 1899. Serial No. 717,191. (No model.)

To all whom it may concern:

Be it known that I, ALVIN BROWN, of Aurora, in the county of Kane and State of Illinois, have invented a new and useful Improvement 5 in Street-Sweepers, of which the following is a specification.

My invention is an improvement upon the street-sweeper for which Letters Patent were granted me, dated June 7, 1898, No. 605,385. 10 There are two principal features of improvement. One is in the peculiar construction and arrangement of the main frame, and the other is in the special construction and arrangement of the dirt-chamber and movable 15 dirt-receptacles, which are so constructed as to be arranged within each of the sweepers to receive the dirt and trash until they are filled and then be run out upon rails or skids to a truck, upon which a number of them at one 20 time are carried away to the dump, while other empty receptacles are placed in the sweepers. This permits the sweepers to keep constantly at work sweeping, saving the time of the sweeper, team, and driver in going to 25 the dump, and permitting one driver and one team to take a number of dirt-receptacles to the dump at one time.

Figure 1 is a side elevation of my improved sweeper. Fig. 2 is a vertical transverse section on line 2-2, Fig. 1, showing the means for transferring the dirt-receptacles to the dump-truck. Fig. 3 is a detail showing the application of skids to the dirt-chamber. Fig. 4 is a perspective view of the dirt-receptacle. 35 Fig. 5 is a vertical longitudinal section through the dirt-chamber, and Fig. 6 is a detail view.

In the drawings, Fig. 1, C are the front wheels, and C' the rear wheels. To the latter is bolted a circular ring of teeth 8, that 40 mesh with a pinion 7 on the upper shaft 5, Fig. 5, carrying sprocket-wheels 3, that drive the endless brush-belt 1. A smaller sprocket-wheel 4 near the ground carries the lower end of the brush-belt and is adjusted both vertically and horizontally by means substantially 45 the same as those shown in my previous patent. The pinion 7 is also provided with a clutch, with operating-lever 11, Fig. 1, toggle-arms 13, and handle-bar 16 for operating them, 50 whereby pinion 7 is thrown into or out of gear with the belt-driving sprocket-wheel 3, all as shown in my previous patent referred to. The

construction and arrangement of the main frame and dirt-receptacles are, however, altogether different, and these I now will proceed to describe. 55

A is a vertical post whose lower end extends below the main rail B and is provided with a hub, in which is rigidly held by a set-screw or key the axle α of the rear wheel C'. This 60 axle passes entirely through the machine, extending between the upper and lower runs of the brush-belt. The main side rails B are made of channel-iron and extend the whole length of the machine, as follows: Commencing at the extreme rear end they run forward horizontally to the vertical posts A. They are let into the inner side of these posts and are firmly bolted to them. From this point they are curved upwardly and forwardly to 70 the rear top corner of the dirt-chamber X. Then they extend horizontally along the top of said dirt-chamber to the front top corner of the same, and from this point they curve downwardly to the level of the driver's platform and extend a short distance horizontally beneath the platform. To support the pinion-bearing of the upper sprocket-wheel, a horizontal bar D, Fig. 1, is bolted at its front end to the upward curve of rail B, between 75 post A and the dirt-chamber, and at its rear end is bolted to the post A. Another bar E is arranged horizontally just above D and parallel with it and is at its front end bolted to the rail B near the top rear corner of the 80 dirt-chamber and at its rear end is bolted to the vertical post A. This bar E carries the rigid fulcrum-bracket of the clutch-lever 11. The top casing-bar F is curved and at its front end is bolted to the rail B at the top 85 rear corner of the dirt-chamber and at its rear end to the top of post A. The two side frames A B D E F are connected together by cross-bars G G G in front and in the rear by the main axle at the bottom of posts A and a 90 cross-bar G' at the top of said posts, as shown in Fig. 1. The special construction of this frame gives it a trussed effect that renders it 95 stiff and strong and well adapted to carrying heavy loads of wet dirt. 100

On the extreme rear end of rail B there is formed an outturned flange b' to receive the set-screw 25 and has a slot b to receive the bolt 24, by which the brackets that carry the

lower brush-wheel are adjusted horizontally, the vertical adjustment of said brush-wheel being effected by screw-rod 17, carrying the axis of said wheel and made vertically adjustable in the slots of the brackets, as shown in my previous patent.

I is an inclined brace connecting the dirt-chamber X to the rail B at a point just in front of the post A. This brace not only stiffens and holds the suspended dirt-chamber, but it is also slotted to receive the hinge-rod 34 of the dirt-pan 33. This rod, with the dirt-pan, in my previous patent referred to is adjusted vertically. In the present case the adjustment is at right angles to the pan and belt-brush, and for this purpose a set-screw 36 is made to work in line with the slot in brace I and adjusts the pan directly to or from the brush. (See Fig. 5). The lower end of this pan has the same lift-rod 40, Fig. 1, and lever 41 for raising and lowering it to or from the ground that is employed in my patent referred to.

The suspended dirt-chamber X is braced in front by an inclined bar J, extending from a point near its bottom up to the main rail B. Said dirt-chamber is formed of horizontal transverse bars G at the top, G' on the sides, and G² at the bottom, of a suitable casing. Transverse guide-bars H are also arranged at the bottom and have edge rails h, adapted to receive the wheeled and movable receptacles R, that receive the dirt and trash. These receptacles are made with the front side higher than the rear and receive the dirt from the brush-belt at the rear over the lower side. The supporting-wheels w are set in recesses along the front and rear sides of the receptacle, so that the latter will fit closely in the chamber X and for the further purpose of housing and covering the wheels w, so that they will not become obstructed with the dirt falling between the receptacle and its case, which would prevent it when loaded from being run out of the casing on the guide-rails. The dirt-chamber is entirely open at its bottom, as shown at Z, and the bars H have attached to their inner sides metal edge plates h, that rise above the level of the bars H and form the bearing-rails for the wheels w, whose bearing, being a thin edge, causes the wheels w to cut through any trash that might accumulate on top of a broad-faced rail. As the dirt is carried up by the brush-belt I over the dirt-pan 33 it is delivered upon a hinged flap e, which is curved and extends into the dirt-chamber and laps over the lower edge of the dirt-receptacle R, as seen in Fig. 5. On the sides of the doors D² of the dirt-chamber there are attached inclined cleat-strips d, which extend over the inclined ends of the dirt-receptacle and prevent dirt from falling down between said ends and the doors. A hinged sheet-metal flap g is also secured to the top of the dirt-chamber and laps down inside the front and higher side of the dirt-

receptacle for a similar purpose. In the top of the dirt-chamber there is also adjustably secured a sheet-metal apron f, which approaches very close to the edges of the brush. This apron is rigidly attached to the slotted arms f', and the slotted arms are adjustably bolted to the top timbers of the dirt-chamber, so that the apron f may be adjusted toward the brush as the ends of the latter wear away. This is an important feature, as in connection with the open bottom of the dirt-chamber it prevents the blast produced by the brush from forcing a cloud of dust over the top of the brush and back toward the rear of the machine. With this apron f the space is reduced to a minimum, and with the open bottom of the dirt-chamber a relief from air-pressure in the dirt-chamber is afforded that causes the smaller dirt particles to settle in the dirt-receptacle. When these movable receptacles are filled with dirt, instead of driving the sweeper to the dump to discharge it, which occupies the time of the sweeper, team, and driver for a long time and only for the transportation of a comparatively light load of sweepings, a long and low-wheeled truck, like a stone-wagon, is lined up beside the sweeper, as shown at Y in Fig. 2, and adjustable skids H' H', with metal bars h' on their upper surfaces, are placed in alignment with the rails H H, with the hooked ends of plates h' resting on a level with the metal rails h and embracing the front sill of the dirt-chamber X and the other ends of the skids resting on the truck. The movable receptacles R are then run out of the sweeper, as in dotted lines, Fig. 2, and over the skids onto the truck, which is built long enough to take the receptacles of a number of the sweepers, usually about four. The sweepers are then supplied with other empty receptacles R and go on with their sweeping while the loaded truck, with its filled receptacles, is driven to the dump, thus doing with one trip and one team and driver the hauling for four sweepers. This, it will be seen, effects a great economy of time and money and makes a valuable and practical system of removing the dirt from the streets without piling it up in the streets, on the one hand, and without undue expense in time and wear and tear on the sweepers involved in hauling the dirt a long distance in the sweepers.

Having thus described my invention, what I claim as new, and desire to secure by Letters Patent, is—

1. The framework for a street-sweeper, consisting of continuous side rails B having their front and rear ends horizontal, with an upward bend near the front for a suspended dirt-chamber, the vertical posts A extended below the side rails B and having at their lower ends, at a point below the side rails, bearings for the wheel-axle, the bars E and D separately bolted in front to the rails B and in the rear to posts A, and bearing respectively a lever-

fulcrum and pinion-bearing, and cross-bars connecting said side rails and posts substantially as shown and described.

2. In a street-sweeper, the combination 5 of continuous side rails B bent upwardly as described; of a suspended dirt-chamber attached at its upper end to the upper bend of said rails, and having inclined braces extending from the lower part of the dirt-chamber 10 to the lower part of said side rails, the rear inclined brace having a longitudinal slot in it, an adjusting-screw working in line with said slot, and a dirt-pan hung to a shaft extending through said slots, and made thereby 15 adjustable to or from the brush in direction at right angles to the lower run of the brush substantially as and for the purpose described.

3. In a street-sweeper, the combination 20 with the dirt-chamber, and a brush delivering into the same; of an adjustable apron or plate fixed to the top of the dirt-chamber opposite that portion of the brush which moves away from the dirt-chamber and into the brush-cas-

ing and made adjustable to the brush substantially as and for the purpose described. 25

4. In a street-sweeper, the combination with the dirt-chamber having an open bottom, and a removable receptacle in the same; of an adjustable apron or plate fixed to the top 30 of the dirt-chamber opposite that portion of the brush which moves away from the dirt-chamber into the brush-casing and made adjustable to the brush substantially as and for the purpose described. 35

5. In a street-sweeper, the combination with a dirt-chamber; of a dirt-receptacle having a high front side, low rear side, and inclined ends, a hinged flap overlapping its low side, a hinged flap overlapping its high side, 40 and an adjustable apron at the top of the dirt-chamber extending toward the brush substantially as and for the purpose described.
